UNITED STATES PATENT OFFICE.

JAMES E. EVANS AND WILLIAM CURTIS, OF DULUTH, MINNESOTA.

TUBULAR HOT-WATER HEATER.

SPECIFICATION forming part of Letters Patent No. 630,674, dated August 8, 1899.

Application filed May 2, 1899. Serial No. 715,349. (No model.)

To all whom it may concern:

Be it known that we, JAMES E. EVANS and WILLIAM CURTIS, citizens of the United States, residing at Duluth, in the county of St. Louis and State of Minnesota, have invented certain new and useful Improvements in Tubular Hot-Water Heaters; and we do hereby declare the following to be a full, clear, and exact description of the invention, such as will enable others skilled in the art to which it appertains to make and use the same.

Our invention relates to hot-water heaters; and it consists of certain novel constructions, combinations, and arrangements of parts, as will be hereinafter more fully described and specifically claimed.

The objects of our invention are to produce a hot-water heater which is exceedingly compact and yet having a large and effective heating-surface and a short and lively circulation, whereby a superior heater is secured which can be operated with a less amount of fuel, occupy less space, and produce more quickly a greater and more constant heat than other hot-water heaters now on the market.

Another object of our invention is to so construct and arrange the tubes that a great number of tubes can be employed in a comparatively small space and as vertical as possible and yet extend over and be in line of the heat from the grate.

We accomplish these objects by the construction shown in the accompanying drawings, in which—

Figure 1 is a perspective view of a hot-water heater constructed in accordance with our invention. Fig. 2 is a top plan view of the return water-legs and connecting-pipes. Fig. 3 is a front elevation of a slightly-modified form of our heater, and Fig. 4 is a side elevation of the upper hot-water tubes leading to the discharge.

As stated above, one of the main objects of our invention is to secure as many pipes as possible and arrange them as compactly and as nearly vertical as possible and yet have them extend over and be brought in contact with the central line of the heat, so that a large heating-surface is secured.

As shown in Fig. 1 of the drawings, the apparatus consists of a base portion A, comprising two horizontally-arranged water-legs

a a', connected by a pipe *a²* with right and left hand threads. The legs *a a'* are provided on one end with suitable caps, which may be removed for cleaning out the said water-legs, and the other end of one of the legs, as *a*, is provided with a pipe connection or intake *x* for water from a suitable source of supply. The pipe *a²* is connected by screw-threaded nipples, by reason of which construction the parts can be readily assembled and disconnected. The water-legs *a a'* are provided with apertures *a³ a³* for the reception of tubes *a⁴ a⁵*. The tubes *a⁴* are approximately short and extend practically vertically and are provided on their upper ends with two-way nipples *a⁶*, into which are screwed tubes *a⁷ a⁸*. The tubes *a⁷* are inclined toward the center of the heater and extend upwardly and are formed with nipples *a⁹* at their upper ends, by means of which they are connected with the drum *a¹⁰* through short connecting-pipes *a¹¹*, which are right and left hand threaded, as are all the connections to facilitate connecting up and disconnecting. The tubes *a⁸* are inclined toward the center of the heater and are carried upwardly to a point on a line with the drum *a¹⁰*, at which point they are provided with nipples *a¹¹*, in which are screwed short connecting-pipes *a¹²*, having on their upper ends screw-threaded nipples *a¹³*, in which latter are secured inwardly and upwardly inclined tubes *a¹⁴*, which latter are provided on their upper ends with nipples *a¹⁵*, in which are screwed short sections of pipe *a¹⁶*, the latter being secured in a horizontally-arranged drum *a¹⁷*. The drums *a¹⁷* and *a¹⁰* are connected by a vertical pipe *a¹⁸*, as clearly shown in Fig. 4, which pipe screws into nipples *a¹⁹ a¹⁹*, provided on the horizontally-arranged drums *a¹⁰ a¹⁷*. The said drums *a¹⁰ a¹⁷* are arranged centrally of the heater and directly in line with the heat and products of combustion, so that the water will be very rapidly heated. By employing two drums the water is divided and a smaller amount thus presented at different points to the action of the heat, which greatly facilitates the heating operation. The upper drum *a¹⁷* leads the water to the different points of distribution.

It will be seen from the foregoing description that the tubes *a⁷* enter the drum *a¹⁰* and that the tubes *a⁵ a⁸* enter the upper drum *a¹⁷*.

Tubes a^{20} , a^{21} , and a^{22} are arranged on the opposite side of the heater, similarly to the tubes a^5 , a^7 , and a^8 , so that the tubes do not extend one above another in parallel lines, but are 5 out of alinement and present the greatest possible heating-surface to the action of the fire, and are exceedingly compactly arranged and as nearly vertical as it is possible to arrange them and yet bring all the tubes at 10 some point in their length centrally over the heat.

In Fig. 3 we have shown a slightly-modified form of construction, in that longer lengths of tubes are employed, and consequently fewer 15 connecting-nipples are required, and the tubes b' in said modification are slightly differently constructed and arranged, as shown, and enter the lower drum a^{10} on the same side on which they are arranged in the apparatus in- 20 stead of on the opposite side, as in Fig. 1. With these slight modifications the constructions are practically the same.

Our invention is confined to a hot-water heater and is not intended as a steam-boiler, 25 as to make an effective steam-boiler it is necessary to return the water a second time through the boiler.

Having now described our invention, what we claim as new, and desire to secure by Let- 30 ters Patent, is—

1. In a tubular hot-water heater, the combination of two centrally and horizontally arranged water-drums located one above the other, horizontal return-water-legs forming a 35 supporting-base for the heater, two sets of tubes connected to the water-legs and inclined upwardly and inwardly and intersecting each other, one set of the tubes entering the lower water-drum and the other set en- 40 tering the upper water-drum and another set of tubes extending from one set of the first-mentioned tubes and inclined upwardly and entering the upper drum which latter drum

leads to the discharge, substantially as de- 45 scribed.

2. In a tubular hot-water heater, the combination of two water-drums, one of which forms a discharge for the hot water suitable return water-legs, one of the legs being an intake for water said legs being connected by 50 a pipe and forming a supporting-base for the heater, and two sets of apertures in each water-leg, tubes secured in said apertures and extending upwardly and crossing each other at approximately the center of the ap- 55 paratus, one set of the tubes from each of the legs entering the lower drum and the other set entering the upper drum and a third set of tubes connected to one set of the tubes from each of the legs which cross each other 60 near the center of the apparatus and extend to the upper drum by means of short sections of pipe connected to the upper ends of said tubes and extending upwardly, substantially as described.

3. In a tubular hot-water heater, the combination of suitable return-water-legs forming a supporting-base for the heater, two sets of tubes connected to the water-legs and in- 70 clined upwardly and inwardly and intersect- 75 ing each other one set of the tubes entering one water-drum and the other set entering another water-drum arranged above the first-mentioned drum, and another set of tubes extending from one set of the first-mentioned tubes and inclined upwardly and entering the upper drum, which latter drum leads to the discharge, and a vertical pipe connect- 80 ing the two drums, substantially as described.

In testimony whereof we hereunto affix our signatures in presence of two witnesses.

JAMES E. EVANS.
WILLIAM CURTIS.
